Patented Mar. 18, 1913.

UNITED STATES PATENT OFFICE.

JOHAN RICHARD FROBERG, OF RICHMOND, CALIFORNIA.

AEROPLANE-RUDDER.

1,056,329.

Specification of Letters Patent. Patented Mar. 18, 1913.

Application filed June 12, 1912. Serial No. 703,180.

To all whom it may concern:

Be it known that I, JOHAN RICHARD FROBERG, a citizen of the United States, residing at Richmond, in the county of Contra Costa and State of California, have invented new and useful Improvements in Aeroplane-Rudders, of which the following is a specification.

This invention relates to aerial apparatus, and particularly to a rudder for aeroplanes.

The object of the present invention is to provide an improved horizontal steering and vertical elevating rudder of unitary substantial construction; said rudder being composed of a main elevating plane and a perpendicularly arranged horizontal steering construction.

Figure 1 is a plan view showing the fuselage of an aeroplane with the rudder attached. Fig. 2 is a front elevation of the rudder partly in section. Fig. 3 is an end view of the rudder. Fig. 4 is a plan view of the rudder-chair. Fig. 5 is a detail showing the rudder and elevator operating device. Fig. 6 is an edge view of the same. Fig. 7 is an edge view of a double pulley block. Fig. 8 is a detail of the elevator clevis.

In the present instance I have shown a fuselage 2 of the top of the aeroplane in which is provided an aviator's saddle 3, adjacent to which is pivoted at 4 a lever 5, the lower end of which is connected by a cable 6 running around a guide or direction sheave 7 to an elevator 8. This elevator is of a suitable transverse section and of appropriate length and width, and is pivoted upon trunnions 9 for transverse oscillation; the trunnions being provided in a chair 10 which preferably is of light, but substantial frame work, a portion of which is suitably transversely braced adjacent its center by bar 11, which is pivoted upon a vertical axis or bolt 12 mounted in the fuselage 2.

The chair 10 is adapted for oscillation about its vertical axis 12 and may be so oscillated by means of suitable cables or flexible connections 13, which extend forwardly from the chair 10 and are wound upon a steering wheel 14 which is pivoted in the upper end of the elevator operating lever 5. The lead wires or cables 13 are preferably crossed below the steering wheel 14 and travel around sheaves 15, thence running downwardly to and around guide sheaves 16

from which the connections run backwardly to and connect with the chair 10.

When the operator wishes to turn the chair angularly relative to the fuselage 2, a turn of the steering wheel 14 effects a pull on one of the connections 13, the consequence of which is the chair will be oscillated in one direction or another, thus presenting to the air suitable blades 17 which are secured to the elevator 8 perpendicularly, the blades 17 forming the rudders accomplishing the horizontal steering of the aerial vessel. Since the horizontal steering rudders 17 are rigidly connected to the elevating device 8, it is manifest that the steering efficiency of the perpendicular planes 17 remains the same, irrespective of the angle of incidents to which the elevator 8 may be adjusted, and it is one of the objects of this invention to so design and provide a substantial, integral and simultaneously adjustable steering and elevating device.

In order to permit the horizontal steering by the rudder 17 without affecting the angle of adjustment of the elevator 8, the connecting cable 6 which runs rearwardly from its connection with the lower end of the elevator lever 5, is connected by a peculiar clevis 20 having double hooks as 21 from which lead strands 22 which run around suitable direction guides 23, thence being continued upward and transversely as at 24 and through a block 25, in the lower part of which is provided a pulley 26 on which the transverse strands 24 travel.

The block 25 is provided with an upper pulley 27, beneath which runs a strand 28 diverging upwardly and connecting to convenient points on the elevator 8. By this construction, when the elevator operating lever 5 is tilted about its fulcrum 4, the operating cable 6 draws, for instance, on the upper stretch, to which is connected a clevis 20, this resulting in pulling downwardly the block 25 and through this drawing down the front edge of the elevator 8; meanwhile the lower stretch of the cable 6 is released or slackened, thus permitting another clevis 20' to slack up respective strands 30 which are connected to a block 31 at the rear edge of the elevator 8. When the operator has adjusted the lever 5 to obtain the desired angle of the elevator, the steering wheel 14 may then be actuated to

swing the chair 10 angularly; the angular movement of the chair with its superposed elevator 8 occurring without interference from the elevator controlling cables by reason of the fact that when the elevator moves about the vertical axis 12, the blocks 25 and 31 will shift transversely along the elevator controlling connections 24. In other words, the blocks 25-31 act as travelers upon the connections 24, the relative movement of the blocks 25-31 being accomplished without transmission of movement to the elevator adjusting mechanism.

The vertical rudders 17 are formed of a peculiar contour; this being illustrated as consisting of a substantially semi-circular curve at its forward perimeter, while the rearmost perimeter is formed with curves, their extremities terminating and intersecting at a point a greater distance from the center of oscillation, as the fulcrum 9, than the approximate center of the forward edge.

The chair 10 may be formed of a light substantial, tubular, or other frame work, the lower portion of which consists of substantial, spaced parallel bars which rest upon and between side bearing guides 32 of the fuselage 2.

Having thus described my invention,

what I claim and desire to secure by Letters 30 Patent, is—

A rudder for aerial apparatus comprising a frame-like chair mounted to oscillate about a vertical axis, means for oscillating the chair about said axis, an elevating plane 35 mounted horizontally on the chair having trunnions at opposite sides about which it is tiltable in a vertical plane, said plane having perpendicular rudders rigid with it, means for oscillating the elevating plane, 40 and means permitting the horizontal steering by the rudders without affecting the angle of adjustment of the elevating plane, said last means comprising an operating cable connecting to the means for oscillating 45 the plane, a pulley block, strands connected to said cable and passing through said block and a strand connected to the block and diverging upwardly and connected to said elevating plane.

In testimony whereof I have hereunto set my hand in the presence of two subscribing witnesses.

JOHAN RICHARD FROBERG.
